UNITED STATES PATENT OFFICE.

ALBERT STEINER, OF CHICAGO, ILLINOIS.

GLOVE-FASTENER.

SPECIFICATION forming part of Letters Patent No. 380,604, dated April 3, 1888.

Application filed September 27, 1887. Serial No. 250,839. (No model.)

To all whom it may concern:

Be it known that I, ALBERT STEINER, a citizen of the United States, residing at Chicago, in the county of Cook and State of Illinois, have invented certain new and useful Improvements in Glove-Fasteners, of which the following is a specification, reference being had therein to the accompanying drawings, in which—

10 Figure 1 is a view of part of a glove showing my improved fastener. Fig. 2 is an enlarged view in detail showing the riveted buttons with their ball-hooks when rivets are used for fastening the buttons to the glove material. 15 Fig. 3 is an edge view showing the parts fastened in full lines, and in dotted lines showing the sewed buttons in position for fastening. Fig. 4 is a face view of Fig. 3. Fig. 5 is an enlarged sectional view of a concave riveted button, and Fig. 6 is an enlarged sectional view of a concave sewed button.

Before describing my invention and improvement I desire to state that I am aware that glove-fasteners have been made with locking ball-hooks. This I broadly disclaim.

The object of my improvement is to prevent the tearing away of the button from the glove material when said button is provided with an offset-fastening, as will be fully understood 30 from the following description and claim, taken in connection with the annexed drawings.

Referring to the annexed drawings, A designates a button, which may be circular, elliptical, or of any other design. This button is 35 represented clearly in Figs. 2, 3, 4, 5, and 6. It is concave on its bottom, and in case of a rivet being used an aperture is made centrally through it for the purpose of receiving a rivet-pin, *a*, which is formed integral with a flat 40 head, *b*, and which, when clinched on the concave bottom, will compress the material between the head *b* and this bottom and prevent a tearing of the material.

It will be observed, by reference to Figs. 3, 45 4, and 6, that I show a button having eyes through it formed with a hook provided with an enlargement on its end and bent so as to interlock with a hook which is a counterpart of it. It will also be observed, by reference 50 to Figs. 2, 3, and 5 of the annexed drawings, that the hooks which are formed on the but-

tons are directed inwardly and outwardly and upwardly and backwardly, so that when they are interlocked the ball tips are in line with each other, (shown in Figs. 1 and 4,) so that 55 the glove or other garment to which the button is attached will be held securely.

The button-hooks by my invention are all formed alike, and when riveted to the gloves are arranged right and left, the hooked and 60 ball extensions being so formed that they will positively interlock and prevent casual detachment.

One essential feature of my improvement consists in a button provided with a hooked 65 extension terminated by an enlargement, said button having a concavity in its back into which the material of the glove will embed itself when the button is sewed or otherwise fastened, thereby preventing the tearing away 70 of the material.

It will be observed from the several figures that the interlocking ball-hooks are formed integral with the buttons, and are projected from the edge of the same, first in an outwardly and upwardly direction with respect to the button, then curved and directed tangentially to the button a short distance, and then curved again and slightly turned in toward the button, where they terminate in a 80 ball. It will thus be seen that when the two adjacent hooks are engaged, as shown in Figs. 1, 3, and 4, the balls will be in line with each other and will be so securely and firmly locked together as not to become disengaged by the 85 ordinary movements of the hand. It will also be seen by the curvature and direction of the hook and the size of the ball on the end thereof that there will not be sufficient space left between the button and the ball to permit the 90 engaging-ball to be unhooked without first moving it to the position shown in dotted lines in Figs. 3, 4, and 5, thereby rendering it impossible to accidentally disengage the hooks. It will be finally seen that I form a concavity 95 in the center of the button, into which the glove material is forcibly embedded and compressed when the same is secured to the glove. This establishes such a substantial bite that the glove material will not tear out under all 100 ordinary usage.

It is essential that the button should present

a broad flat annular surface, e , and an internal concave surface, e' , and that the bar or arch e^2 should also present in cross-section a concave under surface and a convex upper or outer surface, as clearly represented in Fig. 6.

Having thus fully described my invention, what I claim as new, and desire to secure by Letters Patent, is—

The within-described improved glove-fastener consisting of a button having a broad flat

annular surface, e , a concentric concavity, e' , an offset fastening, and a bridge, e^2 , having a concave inner surface and a convex outer surface, as shown and described.

In testimony whereof I affix my signature in presence of two witnesses.

ALBERT STEINER.
